UNITED STATES PATENT OFFICE.

AUGUSTUS A. LOOMIS, OF MUNDELEIN, ILLINOIS.

RAIL TIE.

Application filed January 8, 1926. Serial No. 80,052.

To all whom it may concern:

Be it known that I, AUGUSTUS A. LOOMIS, a citizen of the United States, residing at Mundelein, in the county of Lake and State of Illinois, have invented new and useful Improvements in Rail Ties, of which the following is a specification.

This invention relates to rail ties and more particularly to the means to secure the rails in place.

Briefly stated, an important object of this invention is to provide a rail tie having simple means whereby a rail may be secured to the tie with a cushioning member interposed between the base of the rail and the tie to provide a more yieldable mounting for the rail which increases the life of the track, the life of the rolling stock, and which brings about comfort to the passengers traveling over the road.

A further and equally important object of the invention is to provide a rail tie of the character specified which is of highly simplified construction, durable in use, and cheap to manufacture.

Other objects and advantages will be apparent during the course of the following description.

In the accompanying drawing forming part of this application and in which like numerals are employed to designate like parts throughout the same,

Figure 1 is a detail longitudinal sectional view through the improved rail tie, the rail being shown in section;

Fig. 2 is a vertical transverse sectional view taken on line 2—2 of Fig. 1;

Fig. 3 is a fragmentary group perspective of the improved tie and associated parts.

In the drawing, wherein for the purpose of illustration is shown a preferred embodiment of the invention, the numeral 5 designates a hollow metallic tie having a metallic chair 6 secured thereto by the aid of rivets

7. Fig. 2 plainly illustrates that the rivets 7 not only extend through the top of the hollow tie and the bottom of the chair, but also extend through apertures in the diametrically opposed wings 8 of fastening nuts 9.

It is thus seen that the rivets 7 in addition to securing the chair 6 in place act as a reliable means to hold the nuts 9 in position within the tie 5.

More particularly, the rivets 7 hold the threaded openings in the nuts 9 in register

with the openings 11 in the top of the tie 5 and in register with the openings 12 in the chair. This makes it possible to easily insert bolts 16 through the chair and the top of the tie and thread these bolts through the nuts 9. Figs. 1 and 2 plainly illustrate that the bolts 16 are provided with heads 18 arranged exteriorly of the tie so that the same may be conveniently engaged by a suitable wrench for use in either securing the rail 20 in place or for detaching the bolts so that the rail may be removed for the purpose of renewal, or otherwise.

The bolts 16 carry washers 24 having annular shoulders which overhang the base of the rail and thereby firmly hold the rail in place. Fig. 1 clearly illustrates that the washers not only engage the upper surfaces of the flanges of the rail, but also engage the sides of the base of the rail and, therefore, hold the rail against lateral and upward movements.

Particular attention is directed to the fact that the wing nuts 9 are located within the tie and are, therefore, protected to a high degree from the weather and consequently will not readily rust. This permits the bolts to be detached at any time and also prevents the nuts from being lost.

The chair 6 carries a cushioning element 30 of hard wood or fibre so that the rail is yieldingly supported. This increases the life of the tie and the rail and renders traveling over the tracks more comfortable. The wear on the rolling stock is also substantially decreased by the employment of the cushioning element 30. Fig. 3 illustrates that the ends of the chair 6 are provided with side walls 32 which extend up on opposite sides of the cushion to hold the same in place. The cushion 30 is provided with openings 36 which align with the openings 11 and 12 for the reception of the bolts 16.

With reference to the foregoing description taken in connection with the accompanying drawing it will be apparent that a rail tie constructed in accordance with this invention may be used in lieu of the conventional wooden tie and will last substantially longer and will have the desired cushioning qualities, all of which contributes to the desirability of the tie. As previously stated, the wing nuts 9 are confined within the hollow metallic tie 5 and, therefore, are not likely to rust and are in place for use at any time.

Having thus described the invention, what is claimed is:

1. The combination of a hollow metallic tie, of a chair positioned on the hollow metallic tie and having upwardly directed side walls, and a cushioning element mounted on said chair between said side walls.
2. The combination of a hollow metallic tie, of a chair positioned on the hollow metallic tie and having upwardly directed side walls, a cushioning element mounted on said chair between said side walls, and rail fastening bolts extending through said cushioning element, said chair, and said tie.
3. The combination of a hollow metallic tie, of a chair positioned on the hollow metallic tie and having upwardly directed side walls, a cushioning element mounted on said chair between said side walls, rail fastening bolts extending through said cushioning element, said chair, and said tie, and nuts permanently arranged within the tie and adapted to be engaged by said bolts, there being rivets permanently connecting the nuts to the tie and securing the chair to the tie.
4. The combination of a hollow metallic tie, a chair mounted upon the tie and having side walls, a cushioning element mounted on the chair and confined between said side walls, said cushioning element, said chair, and the top of said tie being provided with

registering openings, a plurality of nuts positioned within said tie and having diametrically opposed wings, rivets extending through said wings, the top of said tie, and said chair, and alining the openings in said nuts with the openings in said tie, said chair, and said cushioning element, and rail fastening bolts extending through said openings and threaded through said nuts.

5. The combination of a hollow metallic tie, a chair mounted upon the tie and having side walls, a cushioning element mounted on the chair and confined between said side walls, said cushioning element, said chair, and the top of said tie being provided with registering openings, a plurality of nuts positioned within said tie and having diametrically opposed wings, rivets extending through said wings, the top of said tie, and said chair, and alining the openings in said nuts with the openings in said tie, said chair, and said cushioning element, rail fastening bolts extending through said openings and threaded through said nuts, and washers mounted on said bolts and engaged with the side edges of the base flanges of a rail, said washers being provided with annular extensions overhanging the base flanges of the rail.

In testimony whereof I affix my signature
AUGUSTUS A. LOOMIS.
